CONVEYER

Tage Georg Nyborg, Worcester, England, assignor
of one-half to The Mining Engineering Com-
pany Limited, Worcester, England

Application September 27, 1933, Serial No. 691,198
In Great Britain October 13, 1932

13 Claims. (Cl. 198—220)

This invention relates to improvements relating to conveyers and has for its object to provide improved arrangements for coupling together the adjacent sections or troughs, more particularly of jiggling conveyers.

There have been various proposals for coupling adjacent sections together by means of wedges, and the present invention is more specifically concerned with an improved device of this description.

In order to couple together the trough sections straps are provided at the ends of the troughs and these straps are drawn and held together. But since the straps generally lie under the overhanging edges of the trough, the vertical movement available for a vertical wedge is limited. The taper of the wedge should be comparatively slight in order that it may maintain its frictional grip.

The idea underlying the invention is to leave the wedge some freedom to move endwise when in its working position, gravity (or possibly spring) action ensuring that it will none the less always tend to work home; but to provide some means (preferably a movable abutment lying against one of the pressure surfaces of the wedge) to ensure that this permitted freedom is not sufficient to enable the troughs to be uncoupled until a releasing movement has been performed which has the effect of increasing the wedge clearance sufficiently to permit of uncoupling by drawing the wedge back without actually removing it. Momentary slackening of the pressure on the pressure surfaces of the wedge is thus immaterial.

A preferred construction is illustrated by the accompanying drawing, wherein

Figure 1 is an elevation and

Figure 2 a plan showing the parts in working position, while

Figures 3 and 4 are corresponding views of the parts prepared for release.

As illustrated the strap 1 at the end of one trough 2 projects more or less horizontally and is spanned by a link or yoke piece 3 pivoted to the strap at 4 so as to be able to swing horizontally. It is of sufficient length to extend beyond the far edge of the strap 5 upon the adjacent trough 6 when the sections are coupled together. An aperture 7 passes through the yoke piece to accommodate a vertical wedge 8 and a movable and lockable abutment is carried in the yoke piece outside the wedge. The movable abutment may take various forms, for example, an eccentric spindle or cam, key or

stepped block, and in a typical form comprises a slideable stepped block or key 9 with locking means as hereinafter described.

The wedge 8 is anchored in the aperture by means of suitable pins 10, 10, rings, or the like at both ends, and the arrangement is such that so long as the abutment formed by the wider portion of the key 9 is in the position shown at Figures 1 and 2 giving minimum wedge clearance, the wedge can be raised to its full height without leaving sufficient clearance for it to be carried round the corner of the second strap 5 when the yoke piece 3 is swung about the strap 1. The stepped key 9 lies within the end of the yoke piece 3 and has a slot 11 cut into its upper face terminating in a through hole 12. A locking pin 13 with an enlarged head 14 is passed upwardly through the yoke piece, the head being however, too large to pass through the upper limb of the latter. The pin 13 is bent over the top of the yoke piece or otherwise prevented from falling back too far. The head 14 of the pin engages in the slot 11 in the sliding key and when the key is pushed into the position giving least wedge clearance or working position as shown at Figures 1 and 2, the head of the pin falls down into the through hole and the key is locked in position until the pin is raised.

In order to release the connection the wedge 8 is knocked up and the pin 13 raised, the key 9 slid back to afford wedge clearance all as indicated at Figures 3 and 4. The link or yoke piece can then be swung out with the wedge held raised, the clearance being now sufficient to swing the wedge 9 free of the second strap 5.

It will be seen that release can be effected at each side of the trough separately without moving the troughs and that a mere momentary loosening of the wedge does not free the joint since there is not sufficient clearance until the abutment has also been freed and moved.

The construction has the further advantage that in case the troughs are to be packed out of line, a reduced portion of the removable abutment may be brought into position behind the wedge and a packing piece inserted between the straps 1 and 5.

To connect the troughs it is sufficient first to hold up the wedge 8 and push in the key 9. The wedge can then be dropped and the locking pin 13 pushed in. The shaking action of the conveyer will itself insure that the wedge comes into its working position and locks the coupling.

It will be observed that there are no loose parts

whatever, the wedge, key and locking pin being all captive and incapable of removal.

The invention provides a swinging link and wedge construction in which there is insufficient wedge clearance for the link to be swung free until a second release operation has also been performed. Other mechanical arrangements may be adopted for the release arrangement; thus for example in one alternative the wedge may be prevented from rising to more than a slight extent, until a locked abutment at its lower end has been released and turned or moved so that it can enter the aperture in the lower part of the strap and various other mechanical equivalents may be adopted without departing from the invention.

What I claim as my invention is:—

1. A coupling for adjacent sections of conveyers comprising a coupling member adapted to hold said sections in coupled relation, a wedge member capable of limited movement when in the working position and adapted to lock said coupling member in the coupling position, the wedge operating to automatically find its way to the end of the limited movement of which it is capable in the working position to draw up the sections, and a movable variable abutment permitting in one position sufficient clearance to the wedge to allow of disconnection of the sections but insufficient clearance in the working position.

2. A coupling for adjacent sections of conveyers comprising a coupling member adapted to hold said sections in coupled relation, a wedge member capable of limited endwise movement when in the working position and adapted to lock said coupling member in the coupling position, and a movable stepped abutment, movement of which into the working position renders the full endwise movement of the wedge member insufficient for the disconnection of the parts, said wedge tending automatically to take its position of minimum clearance.

3. A coupling for adjacent sections of conveyers comprising projections on said sections, a coupling member adapted to couple said projections, a wedge member capable of limited endwise movement when in the coupling position and adapted to lock the coupling member in the coupling position, and a movable member adapted in one position to allow insufficient clearance of the wedge member for disconnection of the parts, said wedge being substantially vertically arranged with its larger end uppermost, the angle of the wedge being less than the angle of friction.

4. A coupling for adjacent sections of conveyers comprising projecting portions on said sections, a swinging coupling member adapted to hold said projecting portions in coupled relation, a wedge member capable of limited endwise movement when in the working position and adapted to lock the coupling member in the coupling position, and a movable stepped abutment in contact with a pressure surface of said wedge member and capable of movement into two positions in one of which it allows sufficient clearance of the wedge member for the parts to be disconnected and in the other of which it does not allow the parts to be disconnected, said wedge tending automatically to move into its position of minimum clearance.

5. A coupling for adjacent sections of conveyers comprising a projection on one of said sections, a swinging link carried by the other of

said sections and adapted to enclose said projection to couple said sections, a wedge passing through an aperture in said link movable endwise to lock said link in the coupling position and capable of limited endwise movement in the working position and a variable abutment situated between a pressure face of said wedge and the end of said link and capable of movement to vary the clearance of said wedge to permit or prevent disengagement of the sections, said wedge tending automatically to take a position of minimum clearance. 80

6. A coupling for adjacent sections of conveyers comprising a projection on one of said sections, a swinging link carried by the other of said sections and adapted to enclose said projection to couple said sections, a wedge passing through an aperture in said link adapted to lock said link in a coupling position and capable of limited endwise movement in the working position, a variable abutment situated between a pressure face of said wedge and the end of said link, and capable of movement to vary the clearance of said wedge to permit or prevent disengagement of the sections and means tending to force said wedge in a direction to reduce its clearance. 90

7. A coupling for adjacent sections of conveyers comprising a projection on one of said sections, a swinging link carried by the other of said sections and adapted to enclose said projection to couple said sections, a wedge passing through an aperture in said link and having limited endwise movement to lock said link in the coupling position, a stepped key situated between a pressure face of said wedge and the end of said link and capable of movement transversely of said wedge to vary the clearance thereof to permit or prevent disengagement of the sections, and means for preventing detachment of the key from the link. 100

8. A coupling for adjacent sections of conveyers comprising a projection on one of said sections, a swinging member carried by the other of said sections and adapted to enclose said projection to couple said sections, a wedge passing through an aperture in said link and having limited endwise movement to lock said link in the coupling position a variable abutment situated between a pressure face of said wedge and the end of said link and capable of movement to vary the wedge clearance to permit or prevent disengagement of the sections, and captive means preventing detachment of said abutment from said link, said captive means allowing movement of said abutment but being adapted to lock it in the position giving minimum wedge clearance. 110

9. A coupling for adjacent sections of conveyers comprising a link for coupling said sections, a projection on one of said sections, a wedge member having limited endwise movement, a variable abutment member situated between a pressure face of said wedge member and the end of said link, a slot in said abutment member having a deepened portion, and a pin having an enlarged head adapted to move in said slot and having a portion cooperating with said link to prevent detachment of said abutment member therefrom, said pin allowing movement of said abutment member to vary the clearance of said wedge member between said abutment and said projection to permit or prevent disengagement of said sections, but being adapted, when its head is in the deepened portion of said 120

- slot, to lock said abutment member in a position preventing disengagement of said sections.
10. A coupling for adjacent sections of conveyors comprising a coupling member adapted to hold said sections in coupled relation, a wedge member adapted to lock said coupling member in the coupling position, a variable abutment movable to vary the clearance of said wedge to permit or prevent disconnection of said sections, 10 said wedge being capable of limited endwise movement in all positions of said variable abutment but tending to take up its position of minimum clearance.
11. A coupling for adjacent sections of conveyors comprising a coupling member adapted to hold said sections in coupled relation, a wedge member capable at all times of limited endwise movement and adapted to lock said coupling member in the coupling position, a variable 20 abutment cooperating with a working face of said wedge and movable to vary the maximum clearance of said wedge to allow or prevent disconnection of said sections, said wedge tending automatically to take up its position of minimum 25 clearance.
12. A coupling for adjacent sections of conveyors, comprising a coupling member adapted to hold said sections in coupled relation, a wedge capable of limited endwise movement in the working position, and a manually adjustable element cooperating with the wedge and serving in one position to permit endwise movement of the wedge to free the coupling and in another position to prevent endwise movement of the wedge from freeing the coupling, said member being without effect on the limited endwise movement of the wedge in working position.
13. A coupling for adjacent sections of conveyors, comprising a coupling member to hold said sections in coupled relation, a wedge cooperating with the coupling member and capable of limited endwise movement in its working position, and means for normally holding the wedge in such relation to the coupling member as to prevent such limited endwise movement from freeing the coupling member, said means being movable at will to afford wedging movement within its limited endwise movement to free the coupling member.
